UNITED STATES PATENT OFFICE.

LEWIS R. HEIM, OF DANBURY, CONNECTICUT, ASSIGNOR TO THE HEIM GRINDER COMPANY, OF DANBURY, CONNECTICUT, A CORPORATION OF CONNECTICUT.

APPARATUS FOR PRODUCING GROUND ARTICLES.

Application filed February 8, 1921. Serial No. 442,117.

This invention relates to grinding and grinding apparatus. One of the objects thereof is to provide an art of grinding which may be readily carried on and which will give dependable and accurate results through long-continued use. Another object is to provide practical grinding apparatus of efficient action and adapted to maintain its parts in proper condition for accurate work. Another object is to provide simple and compact mechanism well adapted for use in connection with the wheels of a grinding machine for cylindrical objects, to maintain such wheels in condition for most effective use. Other objects will be in part obvious and in part pointed out hereinafter.

The invention accordingly consists in the features of construction, combinations of elements, arrangement of parts, and in the several steps and relation and order of each of said steps to one or more of the others thereof, all as will be illustratively described herein and the scope of the application of which will be indicated in the following claims.

In the accompanying drawings, in which is shown one of various possible embodiments of the mechanical features of this invention,

30 Figure 1 is a plan view; and

Figure 2 is a front elevation of the grinding apparatus, the rearwardly extending portions of the several parts not being shown in Fig. 2.

35 Figure 3 is a side view on an enlarged scale of the truing device; and

Figure 4 is a sectional view taken on the line 4—4 of Fig. 3.

Referring more particularly to Figures 1 and 2, it will be noted that there has been provided a main base or standard 10 upon the respective ends of which are pivotally mounted the tables 11 and 12 pivoted thereon as by means of the pins 13 and 14, respectively, indicated in dotted lines in Figure 1. The tables 11 and 12 are each provided with a pair of slots 15 and 16, respectively, through which extend the clamping screws 17 and 18, respectively, for clamping the tables 11 and 12 to the main frame or standard 10 at any desired position to which they may be swung about their pivot pins.

The table 11 is provided with ways 19, in which is slidably mounted the bearing frame 20 which supports the bearings 21 and 22. 55 Housed in the bearings 21 and 22 is a shaft 23 upon one end of which is mounted a suitable chuck 24, in which is adapted to be secured in any convenient manner an abrasive wheel 25, the shaft 23 having mounted upon its other end a collar 26 to prevent axial movement thereof. A pulley 27 secured to the shaft 23 intermediate the bearings 21 and 22 serves to transmit rotation to the abrasive wheel 25 from any suitable source 60 of power as by means of a belt. The bearing frame 20 may be moved longitudinally of the ways 19 and may be clamped in any desired adjusted position by means of the clamping bolts 28.

Upon the pivotally mounted table 12 at the other end of the standard 10 a substantially similar construction is employed for mounting the abrasive wheel 29 in operative relation to the abrasive wheel 25. This construction embodies substantially similar parts and comprises the bearing frame 30 slidably mounted in the ways 31 on the pivotally adjustable table 12, the bearing frame 30 supporting the shaft 32 in suitable bearings 21' and 22' thereon and at one end of which is mounted the chuck 33 for supporting the abrasive wheel 29. A suitable collar 34 is provided upon the end of the shaft 32 to prevent axial movement thereof and a pulley 35 is mounted upon the shaft to transmit rotation to the abrasive wheel 29. The bearing frame 30, however, is provided with a rack 36 facing downwardly and adapted to engage the pinion 37 mounted upon a shaft supported in a suitable bearing 39 preferably integral with the table 12. A lever 39' rigidly secured to the shaft 38 has its end connected to a tension spring 40', one end of which is secured to the standard 10 95 so as to urge the pinion 37 in such a rotative direction as to tend to move the rack 36 and its associated abrasive wheel 29 in a direction toward the abrasive wheels 25. Movement of the bearing frame or carriage 30, and hence of the abrasive wheel 29, in the direction toward the wheel 25 is limited by means of a screw 40 extending through a downwardly extending split arm 41 at the end of

the carriage 30 and adapted to abut against the end of the table 12. The screw 40 may be manually operated to adjust the wheel 29 toward or away from the wheel 25 as desired, and to preserve the adjustment given the screw 40 there is provided a clamping screw 42 at the lower end of the arm 41 to clamp the screw in its adjusted position. A hand lever 43 rigidly secured to the shaft 38 on which the pinion 37 is mounted permits of a manual withdrawal against the action of the spring 40' of the carriage 30 and its associated wheel 29.

The grinding apparatus thus far described is particularly adapted for use in grinding cylindrical bodies, such as rolls for example, and to facilitate its operation upon such articles, a work carrier or rest is employed to support the articles operated upon in proper relation to the abrasive wheels 25 and 29. Such a support or work carrier as is described for example in my United States Letters Patent No. 1,210,936, may be employed and no detailed description of a work rest will be made herein, reference being had to the above mentioned Letters Patent for a possible embodiment of a work carrier particularly adapted for use in connection with the grinding of rolls. When the grinding apparatus is employed for giving rolls a true cylindrical shape, the abrasive wheel 29 is rotated at a relatively high speed in a direction toward the observer, as viewed in Figs. 1 and 2, and the wheel 25 is rotated in a reverse direction at a relatively low speed. The wheel 29 serves to perform the grinding action upon the parts or the rolls supported on the carrier, which extends between the two wheels, and the wheel 25 serves to control or regulate the rate of rotation of the parts or rolls upon the carrier during the action of the grinding wheel 29 thereon.

In the embodiment herein described, the abrasive wheels 25 and 29 are preferably of annular form and are beveled as indicated in Fig. 1 so that upon the proper angular relation between the wheels 25 and 29 having been established by means of the pivotal adjustment of the tables 11 and 12 as hereinbefore described, there will remain a sufficient space between the rear portions of the wheels to permit the discharge of the parts operated upon after their passage between the operative surfaces of the wheels.

It will be understood that the regulating action of the wheel 25 and the grinding action of the wheel 29 upon the articles operated upon is attained by reason of the operating surfaces of the two wheels traveling in opposite directions and that in the embodiment herein described such travel in opposite directions is conveniently accomplished by the opposite rotation given the wheels. I may, however, also employ disc

grinding wheels whose operating surfaces are peripheral, in which instance the wheels are rotated in the same direction for accomplishing the desired travel in opposite directions of the operating surfaces of the 70 wheels. Such a grinding apparatus employing disc wheels is shown, for example, in my United States Patent No. 1,264,930.

In the operation of this grinding apparatus upon cylindrical bodies, for example, the relative action thereon between the regulating wheel 25 and the work carrier above referred to is such that the work, while being ground by the grinding wheel 29 is progressively fed or drawn along the carrier. 80 This automatic feed action takes place by reason of the relative inclination existing between the path of travel of the parts or rolls along the carrier and the path of the operative surface of the regulating wheel 25. By varying this relative inclination any degree or rate of travel or feed of the parts along the carrier may be attained.

In order that the parts operated upon may be given a truly cylindrical form, it is essential that the paths of contact of the operative surfaces of the abrasive wheels 25 and 29 with the parts or rolls be parallel and that such paths of contact be parallel irrespective of the degree of the relative inclination given the path of travel of the parts with respect to the path of the operative surface of the regulating wheel 25. Accordingly there has been provided a means for readily and effectively truing the operative surfaces of the wheels 25 and 29 to present parallel paths of contact to the work for a given adjustment of the rate of feed of the parts.

A post 57, referring more particularly to Fig. 2, is slidably mounted at its lower end in the ways 44 of a secondary frame member and is adjustable in a vertical direction by means of a hand screw 45 rotatably mounted in the lower end of the secondary frame and provided with collars 46 to prevent axial movement thereof. The secondary frame carrying the ways 58 is in turn mounted in ways 47 secured to the front part of the standard 10 of the machine and is movable within the ways 47 by means of the hand screw 48, so that the post 57 may be adjusted longitudinally of the standard 10 of the machine. A set screw 49 serves to lock the post in its adjusted vertical position.

Upon the upper end of the post 57 (see Fig. 3) there is detachably bolted, by means of bolt 84, an L-shaped bracket 58 upon the transversely extending portion of which is provided a pair of lugs 59 in which is pivotally mounted by means of the bolt 60 a guide member 61. A thumb-screw 85 passes through the bracket 58 to form a firm and adjustable support of the bracket 58 to form

- a firm and adjustable support of the bracket 58 upon the post 57. The guide member 61 extends between the abrasive wheels 25 and 29 and at its central portion is provided 5 with a depending lug 62 slotted so as to straddle the clamping bolt 63 extending through the pair of upwardly standing lugs 64 integrally formed with the bracket 58. The guiding member 61 may thus be given 10 any desired inclination with the horizontal plane by swinging the member 61 about its pivot 60 and clamping the guide member 61 in its adjusted position by means of the clamping screw 63.
- 15 The guide member 61 is tapered or beveled in an upward direction, the beveling extending throughout substantially its entire length. The upper beveled portion of the guide member 61 serves as the supporting 20 and guiding surface for a movable carriage 65 whose under side is internally beveled to a corresponding degree. At the lower portion of the guide member 61 is a pair of outwardly extending flanges 66 and 67 adapted 25 to retain the carriage 65 upon the beveled portion of the guide member 61 by means of the L-shaped members 68 and 69 suitably secured to and extending throughout substantially the entire length of the carriage 65,
- 30 the L-shaped retaining members 68 and 69 cooperating respectively with the flanges 66 and 67 of the guiding member 61. The carriage 65 is thus positively retained upon the guiding member 61 and is also positively 35 guided throughout its travel, as will be more clearly hereinafter described.
- At a suitable point on the sides of the carriage 65 there are mounted the abrading tools 70 and 71 adapted to be brought into 40 operative relation with the abrasive wheels 25 and 29 respectively. The abrasive tools 70 and 71 may be made of any material harder than the abrasive material of the wheels 25 and 29 and may conveniently take 45 the form of diamonds. They may be set into the carriage 65 in any suitable manner. In order to advance the abrading tools 70 and 71 throughout the extent of the operative surfaces of the wheels 25 and 29, there is 50 provided a screw 72 threaded into the guiding member 61 and provided at its outer end with a collar 73 and an outwardly extending portion 74 upon which is rigidly fixed a hand wheel 75 for operating the screw 72.
- 55 Intermediate of the collar 73 and the hand wheel 75, the unthreaded portion of the screw member 72 is engaged by the bearing portion 76 of a bracket 77 which is rigidly secured to the front end of the movable carriage 65 as by means of the screws 78. The bearing portion 76 of the bracket 77, being restricted between the collar 73 and the hand wheel 75 on the screw member 72, is thus caused to partake of the same movement as 60
- is the screw 72, while it is threaded into or 65 out of the guiding member 61 and hence the carriage 65 is similarly moved with the bracket member 77. In the position of the several parts, as shown in Fig. 3, the carriage 65 and its associated propelling screw 70 72 are in their innermost position relative to the guiding member 61 and the abrasive wheels 25 and 29.
- The carriage 65 is provided at its upper portion with a reservoir 79, which reservoir 75 is preferably integrally formed with the carriage 65 and extends and is open at its top throughout substantially the entire length of the carriage 65. At points substantially directly over the abrading tools 70 and 71 80 there are provided two channels 80 and 81 leading from the reservoir 79 in the general direction toward the abrading tools 70 and 71 respectively. A pipe 82 provided at its lower end with a valve 83 is positioned directly over the opening in the reservoir 79 and leads from any suitable source of supply of a suitable cooling fluid so that the reservoir 79 may be continuously supplied with cooling fluid. The latter passes 85 through the exit passages 80 and 81 upon the abrading tools 70 and 71 respectively so that the tools are maintained at a suitably low operating temperature during their action upon the abrasive wheels 25 and 29. The 90 streams of cooling fluid, which may be water, are thus made to travel with the abrading tools throughout the extent of their movement and the longitudinally extending opening in the upper portion of the reservoir 79 95 permits the stationary pipe 82 to maintain a constant level of the cooling fluid in the reservoir 79 without the necessity of a flexible connection between the source of supply and the reservoir itself. The pipe 82 may thus 100 be stationarily positioned and the valve 83 permits the adjustment of the rate of flow of the fluid into the reservoir 79 to substantially equal the rate of flow of the fluid upon the abrading tools 70 and 71.
- In operating the truing device hereinbefore described, the relative inclination of the path of travel of the abrasive tool with respect to the path of the operative surface of the regulating wheel 25 is first adjusted to 115 coincide substantially with the relative inclination between the path of travel of the work to be operated upon along the carrier hereinbefore referred to and the path of the operative surface of the regulating wheel 25. Such adjustment of the relative inclination is made to correspond to a given desired rate 120 of feed of the work along the carrier, as has hereinbefore been described. During the operation of the truing device the abrasive wheels 25 and 29 are rotated in such directions as to cause the adjacent operative surfaces to travel in the same direction, and in 125

the embodiment herein disclosed are made to rotate in the direction toward the observer as viewed in Figs. 1 and 2. The operative surfaces of the abrasive wheels 25 and 29 having been preliminarily adjusted into substantial parallelism by means of the pivotally mounted tables 11 and 12, the abrading tool may thereupon be adjusted toward or away from the operative surface of the regulating wheel 25; for example, by means of the hand screw 48, and the operative surface of the other abrasive wheel, as 29, may thereupon be adjusted toward or away from the operative surface of the regulating wheel 25 to any desired degree by means of the hand screw 49. The relative adjustments in the horizontal plane just referred to may be made to determine the amount of material to be removed or abraded from the operative surfaces of the wheels 25 and 29 by the abrading tools 70 and 71 respectively. Adjustment of the abrading tools vertically with respect to the operative surfaces of the wheels 25 and 29 may be made by means of the hand screw 45 and is preferably such as to coincide substantially with the relative vertical adjustment given the path of travel of the work to be operated on with respect to the operative surfaces of the two wheels.

30 The abrading tools 70 and 71 are thereupon advanced across the operative surfaces of the wheels by means of the hand wheel 75 and the screw 72, as will be clear from the description hereinbefore set forth.

35 The abrading tools are thus made to assume a path of travel relative to the operative surfaces of the wheels 25 and 29 as coincides substantially with the path of travel taken by the work to be operated upon relatively to the surfaces of the two wheels. The operative portions of the operative surfaces are thus made accurately parallel with one another and parallel paths of contact of the work to be operated upon with these portions is thus assured, so that accuracy of grinding is attained.

50 It will be noted that the abrading tools and their mountings are readily removed from the post 57 and may be readily replaced by the work carrier to continue the grinding operations and that the truing devices herein described may be readily and conveniently placed in operative position to make possible a quick truing of the operative surfaces of the wheels.

55 It will further be noted that there has been provided in this invention an apparatus and art in which the several objects hereinbefore noted, as well as others of this invention, are attained and in which many advantages are achieved.

60 As many possible embodiments may be made of this invention and as many changes might be made in the embodiment above set forth, it is to be understood that all matter

hereinbefore described and shown in the accompanying drawings is to be interpreted as illustrative and not in a limiting sense.

I claim:

1. In apparatus of the general nature of that herein described, in combination, a grinding wheel normally to be rotated at a relatively high speed, a regulating wheel adapted normally to be rotated at a relatively low speed, said wheels being adapted to present operative surfaces traveling in opposite directions, means for rotating both of said wheels at a relatively high speed, truing means adapted to operate upon both of said wheels, a movable carriage for mounting and advancing said truing means operatively with respect to the operative surfaces of said two wheels, means carried by said carriage forming a trough extending in the direction of advance of said carriage and having an outlet positioned to permit discharge of a cooling fluid from said trough and onto said truing means, and relatively fixed means with respect to which said carriage and trough are movable for supplying cooling fluid to said trough.

2. In apparatus of the general nature of that herein described, in combination, a grinding wheel normally to be rotated at a relatively high speed, a regulating wheel adapted normally to be rotated at a relatively low speed, said wheels being adapted to present operative surfaces traveling in opposite directions, means for rotating both of said wheels at a relatively high speed, a pair of truing tools each adapted to operate upon one of said wheels, a movable carriage for mounting said tools and for moving said tools operatively with respect to the operative surfaces of said two wheels, a reservoir for receiving a cooling fluid mounted upon said movable carriage and having an opening in the upper part thereof extending in the direction of travel of said carriage, means for guiding a stream of cooling fluid from said reservoir onto each of said truing tools, and relatively fixed means for supplying said reservoir with cooling fluid through the opening therein and as said carriage and reservoir are moved relative to said wheels.

3. In apparatus of the general nature of that herein described, in combination, a movable carriage, means for mounting a cutting tool on said carriage, a trough carried by said carriage for receiving a cooling fluid, said trough extending in the direction of travel of said carriage, means for conducting cooling fluid from said trough onto said cutting tool, and means with respect to which said carriage is movable arranged to supply said trough with cooling fluid.

4. In apparatus of the general nature of that herein described, in combination, a grinding wheel adapted normally to be rotated at a relatively high speed, a regulating

wheel adapted normally to be rotated at a relatively low speed, said wheels being adapted to present operative surfaces traveling in opposite directions, means for rotating both of said wheels at a relatively high speed, a pair of truing tools, a movable carriage for mounting said pair of truing tools, each of said tools being adapted to operate on one of said wheels, means for guiding 10 said carriage between said wheels and along a predetermined path of travel, means for adjusting the angular inclination of said guiding means with respect to the path of travel of the operative surface of said regulating wheel, means for locking said guiding means in adjusted position, and means for advancing said carriage along said guiding means.

5. In apparatus of the general nature of 20 that herein described, in combination, a grinding wheel adapted normally to be rotated at a relatively high speed, a regulating wheel adapted normally to be rotated at a relatively low speed, said wheels being adapted to present operative surfaces traveling in opposite directions, means for rotating both of said wheels at a relatively high speed, a pair of truing tools, a movable carriage for mounting said truing tools, each 25 of said tools being adapted to operate on one of said wheels, means for guiding said carriage between said wheels, means for adjusting the relative inclination between the path of travel of said carriage formed by 30 said guiding means and the path of the operative surface of said regulating wheel, means for vertically adjusting said guiding means with respect to one of said wheels, and means for advancing said carriage along said 35 guiding means.

6. In apparatus of the general nature of 40 that herein described, in combination, a grinding wheel adapted normally to be rotated at a relatively high speed, a regulating wheel adapted normally to be rotated at a relatively low speed, said wheels being adapted to present operative surfaces traveling in opposite directions, means for rotating both of said wheels at a relatively 45 high speed, a pair of truing tools, a movable carriage for mounting said truing tools, each of said tools being adapted to operate on one of said wheels, means for guiding said carriage between said wheels, means 50 for adjusting the relative inclination between the path of travel of said carriage formed by said guiding means and the path of the operative surface of said regulating wheel, means adapted to permit adjustment 55 of said guiding means toward and away from the operative surface of one of said wheels, and means for adjusting one of said 60 wheels toward and away from the operative surface of the other of said wheels.

7. In apparatus of the general nature of 65 that herein described, in combination, a grinding wheel adapted normally to be rotated at a relatively high speed, a regulating wheel adapted normally to be rotated at a relatively low speed, said wheels being 70 adapted to present operative surfaces traveling in opposite directions, means for rotating both of said wheels at a relatively high speed, truing means adapted to operate upon both of said wheels, a movable 75 carriage for mounting said truing means and adapted to advance said means into operative relation with said wheels, and means for vertically adjusting said truing means with respect to one of said wheels. 80

8. In apparatus of the general nature of 85 that herein described, in combination, a grinding wheel adapted normally to be rotated at a relatively high speed, a regulating wheel adapted normally to be rotated at a relatively low speed, said wheels being adapted to present operative surfaces traveling in opposite directions, means for rotating both of said wheels at a relatively high speed, truing means adapted to operate upon both of said wheels, a movable carriage for mounting and advancing said truing means in operative relation to said wheels, a reservoir for receiving a cooling fluid mounted upon said movable carriage and movable therewith, and means for guiding a stream of cooling fluid from said reservoir to said abrasive means. 90

9. In apparatus of the character described, in combination, a movable carriage extending longitudinally in the direction of travel thereof, means for mounting a cutting tool on said carriage, a reservoir adapted to receive a cooling fluid mounted upon said carriage and having an opening in the upper part thereof extending longitudinally of said carriage, means for guiding a stream of cooling fluid from said reservoir to said cutting tool, means for advancing said carriage and said reservoir, and stationary means adapted to supply said movable reservoir with fluid through said longitudinally extending opening during the movement of said carriage. 100

10. In apparatus of the general nature of 115 that herein described, in combination, a grinding wheel adapted normally to be rotated at a relatively high speed, a regulating wheel adapted normally to be rotated at a relatively low speed, said wheels being adapted to present operative surfaces traveling in opposite directions, means for rotating both of said wheels at a relatively high speed and in directions to present adjacent operative surfaces traveling downwardly, a relatively fixed guiding member extending between the adjacent operative surfaces of said two wheels and having lat- 120

eral guiding surfaces extending lengthwise upon each of said wheels, and means for thereof but inclined upwardly toward one advancing said carriage along said guiding member. another, a carriage movably supported upon said guiding member and having interior inclined guiding surfaces for coaction with said inclined guiding surfaces of said guiding member, a pair of truing tools mounted upon said carriage, one for action

In testimony whereof, I have signed my name to this specification this 3rd day of January, 1921.

LEWIS R. HEIM.
